STOCKING AND METHOD OF PRODUCING A RAVEL TRAP

Viggo Skole, Laven, Denmark

Application February 21, 1952, Serial No. 272,842

Claims priority, application Denmark February 28, 1951

3 Claims. (Cl. 66—187)

The present invention has to do with knitted stockings and more particularly to stockings of the kind that are knit in the form of a flat blank in a "full fashioned" or straight bar knitting machine, the edges of such blank being subsequently joined in a seam to close the stocking.

It is well known that in such stockings the tip of the toe is one of the places where wear and damage are most likely to occur, and it is therefore customary to provide a special toe reinforcement. Even if such a toe reinforcement is provided, it is found, however, that the tip of the toe is still one of the most delicate parts of the stocking, and if a damage occurs at this point, the wales may ravel in the whole length of the stocking so that the latter becomes destroyed or at any rate must be sent for repair.

It would therefore be desirable to prevent possible damages in the tip of the toe from propagating along the length of the stocking in the form of ravel wales, and it is the object of the present invention to solve this problem in a simple manner without the employment of annoying re-enforcements or stitch patterns in the toe portion and without causing any delay in the knitting operation as such or involving any extra operation. With this object in view, there is provided, according to the invention, a short distance above the tip of the toe of a stocking of the character described, a ravel trap in the form of two rows of interlock stitches diverging in a direction towards the tip from two neighbouring wales in the form of a V.

It is a well known fact that the interlock stitches formed by the so-called widening or narrowing operations (also referred to as "interknitting motions" and in the following sometimes referred to as outward and inward transfer) by means of the narrowing points or transfer needles form a ravel trap, i. e. are capable of stopping the propagation of ravel wales, but in the case of interlock stitches formed by narrowing or widening in the usual way the running stitches may take a path round the inner ends of the rows of interlock stitches and in this manner are capable of circumventing the latter. When, however, the transfer operation is initiated from two neighbouring wales, so that the interlock stitches close together at the middle of the stocking, as provided for according to the invention, there will not be any middle zone through which ravelling may proceed, and accordingly, there is absolute security against the extension of ravelling from any of the wales running into the mouth of the V to other parts of the stocking.

The invention also relates to a method of effecting an outward transfer or widening starting from two neighbouring wales for the purpose of producing a ravel trap of the character referred to. It should be noted that this ravel trap cannot be produced by the ordinary widening operation without any modification. The fact is that in the methods heretofore in use, the widening or outward transfer—like narrowing or inward transfer—is always effected symmetrically, i. e. the transfer is effected simultaneously in both directions. However, if a transfer step is effected simultaneously from two neighbouring wales,

2

the thread lying between the two transferred stitches will not be capable of forming new stitches so that there will be a lack of two stitches during continued knitting. In order to overcome this difficulty and thus to permit the transfer operation to be initiated from two neighbouring wales, i. e. at the middle of the stocking, it is proposed, according to the invention, first to effect one transfer step in one direction only and then to effect a transfer or widening progressively in both directions. Hereby it is obtained that in the first widening or transfer step, a ravel proof interlock stitch is formed at one side in exactly the same manner as when the widening or transfer is initiated with a certain distance between the innermost transfer needles, and in the next following transfer step there is already one wale present between the innermost transfer needles so that there is now no difficulty in effecting a simultaneous transfer in both directions without producing a loose stitch.

The known "full fashioned" or straight bar knitting machines cannot be used without modification to carry out the new method described. These machines are provided with two transfer needle holders which by means of control members are symmetrically displaceable towards and away from one another so that by such displacement, in combination with an upward and downward movement of the transfer needle holders, narrowing and widening operations may be performed. If a machine of this category were used without modification, it would therefore not be possible to effect a series of transfer steps starting from the middle, or in other words, with the transfer needle holders lying close together, because already in the first transfer step, the transfer needle holders would be displaced in opposite directions through a distance corresponding to the distance between two neighbouring needles, whereby, as above described, there would be a lack of two wales during continued knitting.

The invention comprises means for making such a machine suitable for carrying out the particular transfer operation according to the invention without therefore interfering with the symmetry of the widening and narrowing movements of the transfer needle holders desirable in the other phases of the knitting of the stocking. According to the invention, the machine is provided with means adapted, in the position of the transfer needle holders where these lie close together, during downward movement of the transfer needle holders to establish a clearance between the control means and one of the transfer needle holders such that the latter will not take part in the widening movement next following.

The invention will now be described in further detail with reference to the accompanying drawing, in which

Fig. 1 is a diagrammatic view illustrating the toe portion of a flat stocking blank provided with a ravel trap according to the invention,

Fig. 2 is a diagram of the stitch pattern adjacent the zone where the widening or transfer operation for forming the ravel trap is initiated, and

Fig. 3 is a side elevation of a machine showing the more important parts of the transfer apparatus of a straight bar knitting machine for use in the knitting of stockings having a ravel trap according to the invention.

Fig. 1 illustrates how a ravel trap is formed in a stocking in accordance with the principles of the invention, the ravel trap consisting of a V-shaped row of interlock stitches 1 formed by progressive widening or outward transfer starting from the middle of the stocking, or in other words from two neighbouring wales so that the two legs of the V close together in the apex 2 of the V, thereby preventing the occurrence of a middle zone through which ravelling might propagate.

It will be seen that all the tip side wales running into the V are prevented from ravelling past the ravel trap

so that a good security has been obtained against the propagation of damages that might occur in the delicate toe tip.

In the embodiment shown, the widenings forming the ravel trap are followed by a series of narrowings 3, whereby the stockings are narrowed at the tip to a smaller number of wales which are thereafter cut through whereupon the looping and the seaming are effected in the usual manner. However, it would of course also be possible to continue the narrowing practically to the middle of the stocking so that firm selvages are formed practically converging into a point at the tip of the toe only leaving a few wales, whereafter the knitting may be continued in the width determined by these few wales to form a tail such as described in U. S. patent application No. 113,376, filed August 31, 1949, now Patent No. 2,648,210.

In Fig. 1, the toe portion, in which the ravel trap is formed, is diagrammatically illustrated as being reinforced by knitting with double or triple yarns, and while this is of course the preferred arrangement, it is by no means essential for carrying out the principles of the present invention.

In Fig. 2, the two wales from which the local widening is initiated are denoted by the reference characters 4 and 5. The lowermost course in Fig. 2 represents the last course knitted before the widening is initiated. It will be seen that in the next following course a transfer has been effected from the wale 4 to the neighbouring wale 6 at the left hand thereof, whereas no transfer has been effected from the wale 5. In the next following course, a transfer has been made to the left from the wale 6 and to the right from the wale 5, and in each of the following courses, a transfer has been effected in both directions. As is seen in Fig. 2, the direction of the wales is changed by the transfer, and ravelling is rendered impossible owing to the interlock stitches formed by the transfer steps. The widening or outward transfer may be carried out over a greater or smaller number of stitches and need not be effected in each course as shown in Fig. 2. E. g. the transfer might take place in every second course which will ordinarily be the preferred method, but there may, if desired, also be any other interval—within reasonable limits—between the transfer courses. In all cases, stitches starting to run from the tip of the toe will only be capable of running, until they are stopped by an interlock stitch.

Fig. 3 shows an example of how a straight bar knitting machine may be modified to be capable of effecting the transfer operation starting from neighbouring wales at the middle of the blank necessary in order to produce a ravel trap according to the invention. The machine illustrated is of the type having a number of positions for the simultaneous knitting of a plurality of stockings, the machine comprising guiding and controlling means common to all of the positions.

The drawing only shows parts of the transfer apparatus seeing that the other parts of the machine may be constructed in the usual manner. 7 and 8 are two transfer bars extending in the whole length of the knitting machine and each carrying a transfer needle holder 9 and 10 respectively in the zone of each position of the machine. Series of transfer needles or narrowing points 11 are mounted in each of the transfer needle holders. 12 is a control arm serving to move the transfer bar 8 and thereby all the transfer needle holders 10 mounted thereon one way and the other. A corresponding control arm, not shown in the drawing, serves to move the transfer bar 7 and thereby all the transfer needle holders 9 mounted thereon one way or the other. Moreover, the whole of the transfer apparatus, of which the transfer bars form part, is movable up and down. To perform a narrowing or a widening step, the transfer apparatus is first moved down whereby the transfer needles are caused to catch the stitches from the stationary needles of the machine, not

shown, whereupon the transfer apparatus is moved upwards, and the transfer needle holders are displaced in the direction of the transfer bars to an extent such that when the transfer apparatus is again moved down, the transfer 5 needles deliver the stitches to the stationary knitting needles at a displacement corresponding to the distance between two needles.

The control arm 12 and the corresponding control arm for the transfer bar 7 are adapted to carry out symmetrical movements and, in the known machines, are directly coupled to one and the other transfer bar respectively so that the latter are also moved symmetrically. Thus, the two transfer needle holders will e. g. always perform an outward transfer movement in opposite directions at 15 the same time.

According to the invention, the machine has been so modified that in the position of the transfer needle holders where these are situated close together—in which position the machine as ordinarily constructed would not 20 at all be capable of working—a transfer operation in one direction only may be effected so that a ravel trap according to the invention may be formed.

To obtain this, the connection between the control arm 12 and the transfer bar 8 is constructed in a special way. 25 To the transfer bar 8 there is attached a U-shaped bracket 13. An adjustable screw 15 having a head 16 abutting one side of the control arm 12 is screwed through one leg 14 of the bracket 13. A corresponding screw 18 having a head 19 is provided in the other leg 17 of the bracket 30 13, but between the head 19 and the right hand side of the control arm 12 there is provided a vertical slide bar 20 and a sleeve 21, the latter being mounted on a pin-shaped extension of the screw 18 extending through a slot of the slide bar 20. A vertical supporting bar 23 is 35 attached to the outer side of the leg 17 of the bracket 13 and carries an adjustable guide 24 for the vertical slide bar 20 and also an adjustable guide 25 for a second vertical slide bar 26, the latter being further guided by a guide pin 27 mounted on the supporting bar 23 and extending through a slot of the slide bar 26. Each of the 40 slide bars 20 and 26 is provided at its top with a head 28 and 29 respectively abutting opposite ends of a rocking arm 30 rotatably mounted at the top end of the supporting bar 23.

The slide bar 20 is constructed over part of its length with a thickness such that this part of the slide bar together with the sleeve 21 fits tightly between the control arm 12 and the head 19 of the screw 18, the thickness of the slide bar being smaller over a lower portion thereof. 45 The difference between the two thicknesses corresponds to the distance between two neighbouring needles.

At its bottom end the slide bar 20 is provided with a nose 31 having an inclined upper surface 32 for co-operation with an abutment 33 having an inclined lower surface 34, the abutment 33 being displaceably mounted on a block 35 adjustably mounted on a suitable support carried by the frame of the machine, the displacement of said abutment 33 being counteracted by a spring 36. The latter is wound around an adjustable screw 37 carrying 55 an abutment 38 for co-operation with a downwardly extending arm 39 provided at the rear end of the abutment 33, so that the position of the abutment 33 in which it is held by the spring 36 may be adjusted by means of the screw 37.

Also the vertical slide bar 26 is constructed with a thicker and a thinner portion and is provided at its bottom end with a nose 40 for co-operating with an abutment 41 mounted on the same support as the block 35.

A spring 42 and 43 respectively is attached to each of 60 the guides 24, 25 and is constructed with a hook-shaped portion 44, 45 respectively which is urged towards the side of the vertical sliding bars 20 and 26 respectively.

The operation is as follows:

In all the ordinary phases of the knitting operation the 65 transfer apparatus operates as usual, the vertical slide

bar 20 and the sleeve 21 fitting tightly between the control arm 12 and the head 19 of the screw 18 so that there is a positive connection between the control arm 12 and the transfer bar 8. Consequently, the latter will accurately follow the movement of the control arm 12 which is symmetrical to the movement of the corresponding control arm serving to displace the transfer bar 7. In this manner, the transfer needle holders 9 and 10 are moved symmetrically towards one another and away from one another exactly in accordance with the movements imparted to the control arms. It is observed that since there is no necessity of performing a one-sided transfer in more than one direction, the connection between the other control arm and the transfer bar 7 may be constructed in the ordinary manner using permanent and positive coupling means, but if desired, the connection between the last named control arm and the transfer bar 7 may be constructed similarly as the connection between the control arm 12 and the transfer bar 8.

When the production of the ravel trap is to be started, the transfer bars 7 and 8 are moved by means of their associated control arms in such a manner that the transfer needle holders 9 and 10 come into directly abutting relationship as illustrated in Fig. 3. Now, the abutment 33 has been adjusted in a position such that when the transfer apparatus is moved down after the transfer needle holders have been moved to abutting position as described, the nose 31 of the vertical slide bar 30 strikes the abutment 33 whereby the bar 20 is displaced upwards relative to the transfer apparatus. Thereby the thin portion of the bar 20 will come into position between the sleeve 21 and the head 19 of the screw 18, and the bar 20 is held in this position by the spring 42, the hook 44 of the latter engaging below the shoulder formed between the thicker and thinner portions of the bar 20.

Hereby a clearance is established between the control arm 12 and the transfer bar 8, and when the transfer apparatus has been moved down and up, and the control arm 12 and the corresponding control arm for the transfer bar 7 are then displaced in opposite directions, the transfer bar 8 will therefore not follow this movement, but only the clearance between the control arm 12 and the head of the screw 18 will be eliminated in this first transfer step. In this manner, a positive drive connection is again established between the control arm 12 and the transfer bar 8 so that subsequent transfer steps will be effected simultaneously in both directions as usual.

The abutment 41 is so located as to be struck by the nose 40 of the bar 26 when the transfer or widening operation has proceeded to the extent necessary for the desired width of the ravel trap. The bar 26, which by way of the rocking arm 30 was pushed downwards by the upward movement of the bar 20 relative to the transfer apparatus is thereby pushed up again whereby the bar 20 is returned to the position indicated in the drawing by way of the rocking arm 30 so that the thick portion of the bar 20 comes into position between the control arm 12 and the head 19 of the screw 18. In this position of the bar 26, i. e. the position indicated in the drawing, the hook 44 of the spring 43 engages below the shoulder formed between

the thicker and thinner portions of the bar 26 and thereby prevents unintentional displacement of both of the bars 26 and 20. The transfer apparatus has thus been brought in readiness for operating in the ordinary manner.

It will be seen that the special means for establishing a clearance only becomes operative in the case of transfer operations directly from the middle of the blank. In the case of other widening operations not starting from the middle they will be inoperative, and the same applies to narrowing. If the narrowing is continued to the middle of the blank, e. g. in terminating the toe, a situation may arise where the bottom end of the bar 20 will engage the abutment 33 from below upon completion of the last narrowing step. This is why the nose 31 and the abutment 33 are constructed with inclined top and bottom surfaces respectively, and the abutment 33 is mounted for sliding movement against a spring force so that this abutment may yield in this situation.

I claim:

20 1. A knitted stocking comprising a ravel trap provided a short distance above the tip of the toe and consisting of two rows of interlock stitches diverging in a direction towards the tip of the toe from two neighbouring wales. 25 2. In the knitting of stockings, a method of producing a ravel trap comprising, after the knitting of a stocking blank, starting from the upper end thereof, has proceeded to the toe portion of the stocking blank, a wale adjacent the center line of the stocking blank is first transferred outwards in a direction away from the said center line, and in a subsequent course a second wale, which is next adjacent to the first mentioned wale, is transferred outwards in the opposite direction, while a second outward transfer movement is at the same time performed on the first mentioned wale, and additional outward transfer movements are then effected progressively in both directions so as to form two rows of interlock stitches diverging in a direction towards the tip of the toe from the said two next adjacent wales.

30 3. A knitted stocking comprising a ravel trap provided a short distance above the tip of the toe and consisting of a plurality of rows of interlocked stitches diverging in a direction towards the tip of the toe from a plurality of adjacent wales.
